SOLVENT EXTRACTION OF MERCAPTANS

Harry E. Drennan, Hot Springs, Ark., assignor to
 Phillips Petroleum Company, a corporation of
 of Delaware

Application October 22, 1945, Serial No. 623,798

9 Claims. (Cl. 260—609)

1

This invention relates to the preparation of mercaptans. In one of its more specific aspects the invention relates to the segregation of substantially pure alkyl mercaptans from mixtures of the same with hydrocarbons. A preferred embodiment relates to the application of solvent extraction to crude mercaptan oils containing at least four weight per cent mercaptan sulfur to effect the separation of substantially pure mercaptans from closely related hydrocarbon types. A specific modification of the present invention relates to the treatment of mercaptan-hydrocarbon mixtures with aqueous alcoholic alkaline solvents, with subsequent extractive treatment of the mercaptan-rich alkaline solvent to effectively purify and recover said mercaptans.

In the past, interest in the separation of mercaptans from hydrocarbon oils has been almost exclusively confined to petroleum distillates in which small concentrations of mercaptans constituted a nuisance in the finished products. It has long been customary to improve the odor of hydrocarbon distillates by the various sweetening processes in which mercaptans are chemically altered, but not removed. More recently, combustion characteristics of gasolines have been reported as benefiting from complete removal of mercaptans from the distillates. One such process for the removal of mercaptans from hydrocarbons involves the use of caustic-methanol extraction. However, in the treatment of gasoline, the mercaptan sulfur concentration seldom exceeds a few tenths of one per cent of the hydrocarbon material, and subsequent recovery of hydrocarbon-free mercaptans is ordinarily not attempted.

Recent developments in the synthetic rubber industry have created a demand for pure mercaptans of relatively high molecular weight, thus presenting problems of segregation and recovery of such mercaptans not heretofore encountered. Mercaptans suitable for use as modifiers in the manufacture of buna-type synthetic rubbers are ordinarily selected from tertiary types having from about 12 to 14 carbon atoms per molecule. Other heavy mercaptans, such as those of eight and more carbon atoms, are becoming of great interest commercially. Such mercaptans may advantageously be prepared by the catalytic addition of hydrogen sulfide to the corresponding olefins, but in such cases the crude product is almost invariably a mixture of the desired mercaptans with appreciable quantities of unreacted olefin. The actual mercaptan content of typical synthetic crude mercaptan oils may range from

2

about 20 to about 60 weight per cent, with a mercaptan sulfur content, for example in the case of C_8-C_{10} mercaptans, of from about 4 to about 12 weight per cent. These various crude mercaptan oils must be further concentrated to mercaptan assays of at least 90 to 95 per cent before employment as modifying reagents in emulsion polymerizations leading to the production of buna-type synthetic rubbers, or for many other purposes.

The application of vacuum fractional distillation to such crude mercaptan oils may result in the recovery of a relatively pure mercaptan product; however, the difficulties inherent in high-vacuum operations are well known. The existent art pertaining to the solvent extraction of very low concentrations of mercaptans from petroleum distillates is inadequate to solve the highly specific problem of segregation and recovery of relatively pure mercaptans, especially those in the higher molecular weight range, from mercaptan concentrates. This is emphasized by the number of publications on this subject describing solvent regeneration by oxidizing or otherwise destroying the mercaptans and by steam distillation. The present invention is particularly applicable to concentrates of relatively non-volatile and somewhat thermally unstable mercaptans which must be recovered in a pure state, and is preferably utilized for the recovery of mercaptans having four or more carbon atoms per molecule.

An important object of this invention is to prepare pure mercaptans.

Another object is to separate alkyl mercaptans in substantially pure form from admixture with hydrocarbons or other substantially neutral or inert organic liquids.

A further object is to subject mercaptan concentrates formed by the catalytic addition of hydrogen sulfide to olefins, and which contain unreacted olefins, to treatment leading to the ultimate recovery of pure mercaptans free from residual hydrocarbons.

Yet another object is to subject an aqueous alcoholic alkali metal hydroxide solution of mercaptans to a novel series of treatments resulting in the production of pure mercaptans.

A further object of the present invention is to provide specific solvent compositions suitable for optimum results in the extractive treatment of crude mercaptan oils having variable mercaptan concentrations.

A still further object is to provide for the recovery of substantially pure mercaptans from

crude mercaptan oils by a novel combination of extraction operations by means of which the desired mercaptans are transferred from an original high-boiling carrier to a selected low-boiling carrier from which the pure mercaptans can be conveniently recovered by simple evaporation of the final carrier solvent.

These and other objects and advantages of the invention will be apparent, to one skilled in the art, from the accompanying disclosure and discussion.

The process of my invention in preferred embodiment employs as raw feed a crude mercaptan oil of relatively high mercaptan content as compared with sour petroleum distillates. The mercaptan composition of such oils may vary from about 20 per cent to about 60 per cent or even more. A primary extraction procedure is carried out with an appropriate aqueous alcoholic alkali metal hydroxide solution, preferably in the absence of air. Choice of solvent and conditions will be discussed later in detail. Methanol, ethanol, propanol, or other alcohol may be used, though methanol is much preferred. Likewise, sodium hydroxide is preferred among the various alkali metal hydroxides which may be utilized, which include the hydroxides of potassium, lithium, etc. The primary extraction may be carried out as a multistage process with countercurrent flow of oil and solvent, or the extraction may be effected in a packed column with countercurrent flow. In either event, the final rich solvent effluent will be substantially saturated with a mercaptan-oil material comprising a major proportion of mercaptan and a minor proportion of neutral oil, while the lean oil phase will have a mercaptan content of say from 0 to 2 per cent, depending on the initial mercaptan content and on the number of stages employed in the primary extraction. It is an important feature of the invention that at least 90% of the mercaptan content of the crude mercaptan oil is extracted by the primary solvent. Actually, the mercaptan present in the solvent phase is believed to be largely in the form of soluble alkali metal mercaptides, although the exact proportions of mercaptides and of free mercaptans in the rich alkaline solvent are not known.

The next, or secondary extraction, step of the process of my invention comprises the treatment of the mercaptan-rich solvent phase in a certain manner to recover pure mercaptans therefrom. This is effected through the action of a liquid hydrocarbon extracting medium, which preferably is contacted with the rich solvent in at least two stages, separate portions of the hydrocarbons being used in different stages. Preferably used is a low-boiling sulfur-free liquid hydrocarbon, such as propane, butane, pentane, or the like, which may be termed a secondary solvent. The first stage is carried out with extraction conditions particularly chosen so that selective removal of residual heavy oil contaminant from the alkaline solvent is accomplished, the heavy oil being transferred substantially completely to the low-boiling hydrocarbon solvent, generally along with a small portion of the mercaptan. This treatment purifies the alkaline solvent, and may be effected in one or more stages as desired, although a single step is ordinarily quite adequate. After this complete removal of residual heavy oil, the alkaline solvent is contacted with another portion or portions of the low-boiling secondary solvent in one or more stages under different conditions regulated to transfer the mercaptan from

the former to the latter. The thus-denuded alkali solvent is recycled to the primary extraction step.

The final operational step of my process is the recovery of product and of hydrocarbon solvent. The hydrocarbon solvent is reclaimed by simple evaporation or distillation. The stream from the first stage secondary extraction yields a residue comprising heavy oil and some mercaptan, which residue is preferably recycled to the primary extraction step for ultimate recovery of the mercaptan, while the rich solvent stream from the last stages yields a residue of high purity mercaptan product. Streams from intermediate stages, if any, are recycled to the primary extraction step or yield mercaptan product, depending on their content of heavy oil. The recovered low-boiling secondary hydrocarbon solvent is combined for reuse in the various steps of the secondary extraction step.

In order to illustrate and exemplify my invention, the accompanying drawings are provided. Figure 1 is a simplified flow diagram in somewhat schematic form, showing one arrangement of apparatus elements and flow of materials therethrough suitable for practicing the invention in a specific and preferred embodiment. Figure 2 is a series of curves inter-relating the solvent composition with the mercaptan sulfur content of the crude product being treated and the temperature of extraction. With respect to Figure 1, it will be appreciated that the drawing is only schematic and not necessarily drawn to scale, and that all of the elements of auxiliary apparatus such as valves, liquid level controllers, temperature controllers, heaters, coolers, etc. are not shown in order to avoid burdening the drawing with too much detail, for these and other elements are readily understood and supplied by one skilled in the art.

Referring now to Figure 1, crude mercaptan oil is charged through line 1 and rate control valve 2 to the inlet side of mixing pump 3. Simultaneously a regulated flow of aqueous caustic-methanol solvent from settling tank 9 is introduced into line 1 via line 21 and the rate controlling valve 20. The solvent and oil phases, after thorough commingling in pump 3, are discharged through pipe 4 into settling tank 5 where gravity separation of the phases occurs. The mercaptan-bearing oil phase is then withdrawn through line 6 and charged to pump 7 for the second stage extraction, while the solvent phase is continuously removed to the rich solvent tank 24 by way of valve 22 and transfer line 23. Solvent for the second stage extraction is derived from settling tank 13 and is charged to pump 1 through valve 19 and line 18. The emulsion from pump 7 is discharged through pipe 8 to settling tank 9 from which the oil phase is removed by line 10 to mixing pump 11 while the solvent layer is sent to the first stage pump 3 as previously described. The third stage extraction of the mercaptan oil is carried out in mixing pump 11 where the now relatively lean oil is contacted with fresh or regenerated caustic-methanol solvent transferred from solvent tank 25 through flow-control valve 29, line 26, pump 21 and pipe 28. The third-stage emulsion is discharged by way of line 12 into tank 13 from which the separated and substantially mercaptan-free oil is passed through pipe 14 to tank 15 for further separation of solvent and oil phases. The mercaptan-denuded oil is finally sent to storage through line 16 while the once-used solvent in tanks 13 and 15 is sent

to the second stage mixing pump 7 through valves 18 and 17 and transfer line 18.

The secondary extraction step involving the removal of absorbed oil and mercaptan from the aqueous caustic-methanol solvent is illustrated as a two stage operation employing a light hydrocarbon such as pentane, butane or the like as the secondary solvent phase. The mercaptan-containing caustic-methanol aqueous solution from the primary extraction step is withdrawn from tank 24 through flow-control valve 30 and thence by line 31 to pump 32 where it is thoroughly agitated at a low temperature with a predetermined volume of pentane flowing from tank 33 via rate-controlling valve 31, line 34, pump 35 and line 36. The resulting emulsion is discharged from the mixing pump through pipe 38 into settling tank 39 where phase separation occurs. The pentane layer, containing mainly absorbed heavy neutral oil along with a minor amount of mercaptan, is continuously removed to storage tank 41 through pipe 40. The caustic-methanol phase which is now substantially free of neutral oil is passed via valve 42 and line 43 to pump 44 where it is extracted at a considerably higher temperature with pentane flowing from tank 33 through valve 37, line 34, pump 35, line 36 and line 45. After a suitable contact period, the emulsion is discharged from the pump into line 46 and thence into settling tank 47 for phase separation. The now mercaptan-rich pentane phase is continuously withdrawn to storage tank 68 through pipe 48. Subsequent process steps involving the denuded caustic-methanol phase depend on the quantity of pentane in this phase, which in turn is dependent on the operating conditions. If the proportion of pentane is small, the caustic-methanol phase is pumped to storage tank 25 by way of valve 49, line 50, valve 110, line 63, pump 64 and line 66. On the other hand, if the caustic-methanol solution contains a considerable quantity of pentane, valve 110 is closed and valve 111 opened, and the solution is transferred via valve 49, pipe 50, valve 11, and pipe 112, to pump 51 and thence through heat exchanger 52 to stripping column 53, which is operated in a conventional manner, with additional heat being supplied by means of steam coil 54. The pentane is taken overhead through line 56, condenser 57, and line 58 to accumulator tank 59 and thence to pentane storage tank 33 through valve 60 and lines 61 and 62. The now pentane-free aqueous caustic-methanol solvent is removed from the stripping column through valve 65, line 63, pump 64, line 66, and heat exchanger 67 to storage tank 25. The water-caustic-methanol solution in tank 25 is ready for use in the primary extraction operation as described above.

The final sequence of operations involves the recovery of the mercaptan product and the pentane solvent from the oil-mercaptan-pentane solution accumulated in tank 41 and the main mercaptan-pentane solution in tank 68. The oil-rich pentane solvent is withdrawn from tank 41 through valve 69 and line 70 by means of pump 71, with subsequent discharge from said pump into line 72, heat exchanger 73, and stripping column 74, which is operated in a manner known to the art. Heat may be supplied to the column by steam coil 75, and operating temperatures and pressures are selected in accordance with the type of hydrocarbon solvent involved. The hydrocarbon, in this instance pentane, is removed overhead through line 76 and is condensed in condenser 77, from which the con-

densate is discharged via line 78 into accumulator 79. Pump 81 is used to transfer the recovered pentane from tank 79 through valve 80 and pipes 82 and 62 to storage tank 83. The recovered pentane solvent is then ready for recycling to the secondary extraction steps as previously described. The pentane-free neutral oil-mercaptan blend is removed from column 74 through valve 83, line 84, heat exchanger 85, pump 86, and line 87, and may be partly or completely passed to storage tank 89 through valve 88. A portion or all of this oil is preferably recycled to the primary extraction step by way of line 87 and valve 90 for ultimate complete recovery of the mercaptan content and rejection of the oil content. This may be done continuously, or the oil may be withdrawn intermittently from storage 89 by way of valve 109, pump 86, line 87, and valve 90.

The mercaptan-rich pentane solvent from the second stage of the secondary extraction step in tank 68 is treated for recovery of the substantially pure mercaptans. The pentane solution is charged to conventional stripping column 96 by way of valve 91, line 92, pump 93, line 94, and heat exchanger 95. Additional reboiler heat may be furnished to the column by means of steam coil 97 and the column is so operated as to furnish a pentane overhead product and substantially pure mercaptan as the kettle product. The pentane is conducted through pipe 98 to condenser 99 and thence via line 100 into accumulator 101. The cooled solvent is then pumped to storage tank 33 by way of valve 102, pump 103, line 104, and line 62. The pentane-free mercaptan product stream is withdrawn from column 96 through valve 105 and line 106 to the desired utilization.

The process of the present invention is especially directed toward the recovery of mercaptans from relatively concentrated solutions in hydrocarbons as distinguished from the low mercaptan concentrations of sour petroleum distillates. More particularly, concentrates produced in the synthesis of mercaptans from hydrogen sulfide and olefins are suitable for extractive treatment. However, similar mercaptan concentrates from different sources are also amenable to treatment by my process. Although the alkyl mercaptans are ordinarily of greatest interest, the alkenyl, cycloaliphatic, and various substituted mercaptans are likewise recoverable. Ordinarily, hydrocarbon-mercaptan blends having mercaptan contents ranging up to 75 per cent by weight or even higher can be profitably treated for mercaptan recovery, while the most economically favorable concentrations are those of about 20 to 60 per cent based on RSH assay or from about 4 to about 12 per cent based on mercaptan sulfur content. In the case of a very high mercaptan content, say 80 to 90 per cent or more, the concentrate may advantageously be diluted down to a lower mercaptan content with pentane or other suitable hydrocarbon in order to facilitate handling in the primary extraction. Or, less preferably, the primary extraction may serve to dissolve the mercaptan concentrate substantially completely, with the multistage secondary extraction serving to remove neutral oil and give a pure oil-free mercaptan product.

The solvent employed in the primary extraction of the present invention is an aqueous alcoholic alkali metal hydroxide solution, strong with respect to the hydroxide, and having a water-alcohol ratio selected within critical limits. I prefer

to use sodium hydroxide-methanol-water solutions. While similar solutions have been used before in the extraction of mercaptan impurities from gasoline, a single composition of solution sufficed for such use. In contrast, I have found that no single solution is adequate for the total range of sulfur concentrations usually encountered in the processing of mercaptan concentrates by this invention. With a given quantity of alkali hydroxide per unit of sulfur content of the mercaptan concentrate (a matter which will be discussed later in detail), the volume ratio of water to methanol in the solvent has been found to be extremely critical in the successful operation of the primary extraction step. Thus, if this ratio is too low an excessive quantity of neutral oil will be absorbed along with the mercaptan, while if this volume ratio is too high inadequate mercaptan absorption will occur. I have found that the optimum solvent is one which will absorb from at least about 65 on up to 70 weight per cent of the mercaptan sulfur from the crude mercaptan oil in a single-stage equilibrium extraction at a selected temperature level, preferably within the range of about 40 to about 120° F., when a sodium hydroxide : total sulfur weight ratio of 2:1 is used. Such a solvent effects 90 to 95 per cent sulfur absorption in a three-stage countercurrent primary extraction of the type described above with reference to the drawing. Further, the rich solvent obtained from the three-stage operation, with conditions which gave 65 per cent sulfur absorption in one stage, showed the highest recovery of pure mercaptans per pound of sodium hydroxide in the solvent. If a true countercurrent extraction, rather than a three-stage contacting, is used, the same solvent is best, and extremely high through-put rates have been found feasible in using a packed tower and still effecting substantially complete sulfur removal.

The temperature range of 40 to 120° F. encompasses the readily attainable atmospheric and near-atmospheric temperatures. While one might operate outside this range, it is not practical to do so, and the advantageous efficiencies of my process would thereby be greatly minimized or lost.

The water to methanol volume ratios used range from 0.8:1 to 1.5:1. The sodium hydroxide content thereof preferably ranges from 36 weight per cent in the 0.8:1 solvent down to 28 weight per cent in the 1.5:1 solvent, although considerable latitude is permissible since the volume of solvent is selected so as to give the desired 2:1 weight ratio of NaOH to sulfur in the crude mercaptan oil being treated. However, the NaOH content of the solvent is preferably always at least 20 per cent, since the use of too dilute solutions require an otherwise unnecessarily large volume of solvent. The specific figures of 36 to 28 weight per cent just given are those obtaining when the strongest 0.8:1 solution is prepared by the preferred method of dissolving 10 pounds of sodium hydroxide in 1.057 gallons of water, and then adding 1.321 gallons of methanol while maintaining the temperature of the solution below about 140° F. This is the strongest NaOH-methanol-water solution readily made and stored at ordinary atmospheric temperatures. The other solvents of different water : methanol ratios are readily prepared in the same manner, using correspondingly larger amounts of water. If in a given plant a number of crude mercaptan oils of different sulfur contents are liable to be encountered, and/or if extraction conditions are apt

to vary considerably from time to time, it is most convenient to have available a standard stock solvent which can be used per se in some instances and to which water may be added to obtain the various other water : methanol ratios needed. Such stock solution is most conveniently the strong solution prepared as just described, containing 36 weight per cent NaOH and having a water : methanol ratio of 0.8:1.

10 The critical interrelationships of solvent composition, feed mercaptan sulfur concentration, and temperature, adverted to above, are shown in Figure 2. This figure presents a series of curves from which the appropriate solvent water : methanol volume ratio can be read directly for operating temperatures between 20 and 120° F. and for feed stocks having mercaptan sulfur concentrations between 4 and 10 weight per cent.

To illustrate the use of Figure 2, the recovery of mercaptans from a crude C_{10} to C_{14} mercaptan concentrate having a sulfur content of 5.5 weight per cent may be considered. If it is desired to carry out the primary extraction at 100° F., reference to Figure 2 reveals that curve 3 passes through the locus of 5.5% sulfur and 100° F. Curve 3 represents a water : methanol volume ratio of 1.0:1.0. The extraction is therefore to be effected with a solvent having this ratio, utilizing a sufficient volume of the solvent that two parts by weight of NaOH are used per one part by weight of sulfur. The result is the desired 90% absorption of the mercaptans in a three-stage equilibrium contacting (curve 3 representing the solvent which gives 65% absorption in a single stage at the given conditions).

Supposing, by way of further illustration, that it is desired to do the extraction at 90° F., rather than 100° F., an examination of Figure 2 shows that the locus of 5.5% sulfur and 90° F. falls approximately half-way between curves 3 and 4. Since curve 4 is the 1.1:1.0 ratio, it is obvious that a solvent having a 1.05:1.0 ratio of water to methanol will accomplish the same results as were accomplished at 100° F. with the 1.0:1.0 ratio. However, since the permissible single-stage extraction efficiency ranges from a minimum of 65% up to a maximum of 70%, or even 75%, some latitude in the adjustment of water:methanol ratios is obviously allowable while still remaining within the given range. The curves in Figure 2 are so selected to take care of this latitude, and whenever the given conditions indicate a ratio between the curves, the solvent defined by the curve representing the lower water-methanol ratio may be used. Thus, while the upper limit of 70-75% single-stage extraction is not set out in Figure 2, such limit is approximated by the next higher curve in the series. In other words, curve 3 represents the solvent to be used for all conditions falling on it or lying above it up to curve 4, curve 4 is good for all conditions up to curve 5, et cetera. In the specific case in question, involving a 5.5% sulfur oil and a temperature of 90° F., the data from which Figure 2 was derived show that use of the 1.0:1.0 solvent (curve 3) effects 68% extraction in a single stage (which is above the lower limit of 65%, but below the 70-75% upper limit beyond which too much neutral oil is absorbed), or 94-95% extraction in the three stages. Each curve in Figure 2 shows the maximum temperature at which that particular solvent may be used for an oil of given sulfur content. However, temperatures lower by as much as 10 to 15° F., on the average, may be used with that solvent and 75 sulfur concentration, without dissolving so much

mercaptan and oil as to exceed the limits mentioned above.

In order to realize the most efficient and economical extraction in the primary step, the solvent selected, as previously described, should be used in such volumes during the contacting periods as to contain about 2 parts by weight of sodium hydroxide or its equivalent for each part by weight of mercaptan sulfur in the charge stock. This is equivalent to a mol ratio of alkali metal hydroxide to mercaptan of 1.6:1. Using this ratio, the oil to solvent volume ratio may vary from about 3:1 for mercaptan oils containing 4 per cent mercaptan sulfur to about 8:1 for oils having 10 per cent mercaptan sulfur, when using the above-described stock solution or dilutions thereof. I have found that the 2:1 weight ratios for NaOH : S is the minimum that can be used with practical efficiency, while the use of a higher ratio gives only very little improved results. A plotting of weight ratio of sodium hydroxide to sulfur content against the percentage sulfur extracted shows a remarkably sharp break at the 2:1 ratio.

Turning now to the secondary extraction, in which the residual oil and the mercaptans are separately removed from the rich caustic-alcohol-water solvent, the preferred secondary solvents to be used for this purpose are the low-boiling hydrocarbons such as propane, butane, isobutane, pentane, isopentane and selected fractions of natural gasoline. Conversely, if the process is applied to light mercaptans, heavier hydrocarbons of boiling range dissimilar to that of the mercaptans and of the oil in the crude mercaptan charge may be employed, from which the mercaptans may be flashed or distilled overhead. The solvents used are ordinarily paraffinic, but may be partly or totally composed of olefinic, cycloparaffinic, and/or aromatic hydrocarbons. Other organic liquids, such as chlorinated hydrocarbons, certain amines, etc. may also be used. The only requirement is that the secondary solvent be essentially insoluble or of only limited solubility in the aqueous alcoholic alkaline primary solvent, and substantially inert thereto and to the mercaptans under the conditions of use.

In the first stage of the secondary extraction, the mercaptan-rich caustic-alcohol solvent may advantageously be contacted with, say, an equal volume of the selected hydrocarbon or other organic secondary solvent in order to absorb the neutral oil preferentially. It is an important feature of the invention that this operation is carried out at relatively low temperatures of about 30 to about 65° F. I have found that this very effectively suppresses the extraction of mercaptans, while removing substantially all the dissolved neutral oil from the caustic solvent. Approximately five volumes of hydrocarbon per volume of neutral oil present in the rich solvent should be used at the aforesaid temperatures to obtain this complete removal in a single stage. In the subsequent secondary stage or stages, I ordinarily prefer to employ 2 or more volumes of hydrocarbon per volume of mercaptan-containing primary solvent in order to minimize the number of required stages. I have found that this latter mercaptan extraction operation is favored by elevated temperatures in the range of about 100 to about 150° F. or somewhat higher. Ordinarily from 80 to 90 per cent of the mercaptan content of the primary solvent is transferred to the hydrocarbon secondary solvent in

one treatment under these conditions. The remarkable effectiveness of this two-stage secondary extraction will be apparent from the specific example given hereinafter.

5 I have found that the recovered caustic-alcohol primary solvent can be repeatedly used in the cycle of operations of this invention without material loss of solvent efficiency. However, minor losses of alcohol may be encountered in 10 prolonged use and may require occasional additions of make-up alcohol. Thus, the residual oil remaining after extraction of mercaptans therefrom may contain, under extreme conditions, from 0.2 to 0.5 per cent alcohol. This, of 15 course, may be recovered if desired, but this is not usually economically advantageous. The secondary solvent ordinarily carries a small amount of alcohol around in its circuit but so long as the alcohol is lower-boiling than the 20 mercaptan, or higher-boiling if a higher-boiling secondary solvent is used, it is recovered with the secondary solvent.

The final recovery of the mercaptan product is accomplished in most instances by simple flash 25 distillation of the secondary hydrocarbon solvent or by conventional stripping or distillation in columns of moderate efficiency. With mercaptans having from 10 to 14 or more carbon atoms per molecule, stripping column temperatures 30 should not exceed about 320° F. in order to prevent decomposition of the product, and temperatures above this value are completely unnecessary due to the choice of a low-boiling hydrocarbon as the secondary solvent.

35 The following specific example is offered in further illustration of my invention. However, this example is not to be construed as an undue limitation of the scope of the invention.

The crude mercaptan oil employed in this 40 experiment was obtained by the catalytic addition of hydrogen sulfide to an olefin polymer fraction obtained by the polymerization of refinery butylenes and having 10 to 14 carbon atoms per molecule. Analysis of the mercaptan-olefin mixture showed a mercaptan sulfur content of 6.5 45 per cent by weight.

The preferred solvent to be used in the primary extraction of this material was determined by referring to Figure 2 which indicates a methanol: 50 water volume ratio of 1.0:1.0 for operating temperatures in the range of 95 to 115° F. The solvent, prepared by adding the calculated volume of water to the standard stock solvent defined above, contained 0.413 g. of NaOH per milliliter. To start the countercurrent three-stage extraction, 20 ml. of aqueous caustic-methanol solvent was added to each of three contactors. Fresh mercaptan oil (80 ml.) was added to the first stage where contacting for a period 60 of 30 seconds was completed, followed by separation of the phases. The oil phase was then introduced into the second stage contactor for similar treatment, and thence to the third stage contactor. Following this preliminary run, the 65 solvent phase from the second stage was transferred to the first stage and the solvent from the third stage was moved into the second stage, while fresh solvent was added to the third stage in preparation for the second cycle involving another 80 ml. charge of fresh mercaptan concentrate. This countercurrent movement of oil and solvent was continued until the effect of the starting solvent had been eliminated as indicated by constant volume and sulfur values in the 70 effluent lean oil from the third stage and a con-

stant volume for the rich solvent from the first stage contactor. Representative equilibrium data then obtained are presented in Table I:

TABLE I
Primary three-stage extraction of crude mercaptan oil with water-methanol-sodium hydroxide solvent

	Oil Phase			Solvent Phase	
	Charge Vol., ml.	Effluent Vol., ml.	Effluent S, wt. %	Charge Vol., ml.	Effluent Vol., ml.
1st Stage-----	80	62	2.6	26	54
2nd Stage-----	52	47	1.5	21	26
3rd Stage-----	47	46	0.7	20	21

The mercaptan-rich solvent phase recovered as effluent from the first stage of two identical runs effected as above, was subjected to a two-stage secondary extraction with pentane. The first-stage secondary contacting was carried out at 63° F. using an equal volume of the pentane secondary solvent per volume of rich primary solvent. This initial extraction removed neutral oil in admixture with mercaptans, which can be retreated in the primary extraction along with the crude charge, or less preferably, in a separate primary extraction. The second stage secondary extraction involved treatment of one volume of the water-caustic-methanol solution from the first stage with twice its volume of pentane at a temperature of 100° F. The equilibrium product balance from the two-stage secondary extraction after removal of pentane by distillation is given in Table II.

TABLE II
Secondary two-stage extraction of mercaptan-rich water-methanol-sodium hydroxide primary solvent with pentane secondary solvent

	C ₆ -C ₁₄ Mercaptan, ml.	Neutral Oil, ml.
1st Stage Pentane Phase-----	20.8	21.2
2nd Stage Pentane Phase-----	21.5	None
2nd Stage Primary Solvent Phase-----	6.0	None

While I have described my invention in detail with the inclusion of certain specific embodiments, no undue limitations are thereby intended other than those imposed by the claims.

I claim:

1. A process for the manufacture of high-boiling mercaptans which comprises effecting the catalytic addition of hydrogen sulfide to an olefin polymer fraction having not less than 10 and not more than 14 carbon atoms per molecule under conditions producing a crude mercaptan oil containing at least 4 weight per cent mercaptan sulfur and comprising mercaptans having not less than 10 and not more than 14 carbon atoms per molecule and the corresponding unreacted olefin, subjecting said crude mercaptan oil to extraction with a sodium hydroxide-methanol-water solvent containing at least 20 weight per cent sodium hydroxide, at a temperature within the range of 40° F. to 120° F., in quantities such that the ratio of the weight of sodium hydroxide in the solvent charged to said extraction to the weight of sulfur in the crude mercaptan oil charged to said extraction is 2:1, said solvent having a water:methanol volume ratio between

0.8:1.0 and 1.5:1.0 and selected so that a single-stage equilibrium contacting of said solvent and said oil at the aforesaid conditions would effect the solution in said solvent of at least 65 per cent but not more than 70 per cent of the mercaptans from said oil, effecting said extraction in three stages with the oil and the solvent flowing countercurrently through said stages, thereby extracting at least 90 per cent of the mercaptans from said oil, discharging residual olefinic oil from said extraction, contacting the mercaptan-rich solvent from said extraction with about five volumes of liquid pentane per volume of residual olefin dissolved in said rich solvent in a single stage at a temperature not greater than 65° F. thereby desorbing into said pentane substantially all of the olefin from said rich solvent, contacting the thus-treated mercaptan-containing solvent with about twice its volume of pentane in a single stage at a temperature of at least 100° F. to desorb mercaptans from said rich solvent into said pentane, and evaporating said pentane from the resulting mercaptan-pentane solution to recover said mercaptans substantially free from residual olefins.

2. A process according to claim 1 further characterized by evaporating pentane from the pentane-olefin-mercaptan solution formed by said first contacting of pentane with mercaptan-rich solvent, thereby leaving a residual mixture of olefin and mercaptan, returning said residual mixture to further extraction with sodium hydroxide-methanol-water solvent for ultimate recovery of the mercaptan content thereof and discharge of the olefin content thereof, evaporating pentane dissolved in the mercaptan-stripped solvent and returning resulting lean solvent to contact with further amounts of crude mercaptan oil, and combining the three portions of evaporated pentane for re-use in contacting mercaptan-containing solvent as described.

3. A process for recovering mercaptans from a crude mercaptan oil containing a hydrocarbon oil and having a mercaptan sulfur content of at least 4 weight per cent, which comprises intimately mixing said crude mercaptan oil at a temperature lying between about 40 and about 120° F. with sufficient of a primary solvent consisting essentially of sodium hydroxide dissolved in a mixture of water and methanol to give a sodium hydroxide:sulfur weight ratio of approximately 2:1, the water:methanol volume ratio of said solvent lying between about 0.8:1.0 and about 1.5:1.0 and selected so that from about 65 to about 75 per cent extraction of the mercaptan content of the crude mercaptan oil would be effected in a single-stage equilibrium contacting at said temperature, discharging undissolved mercaptan-denuded hydrocarbon oil from said mixing step, withdrawing from said mixing step primary solvent containing mercaptans and some hydrocarbon oil dissolved therein and intimately contacting same with a first portion of a secondary solvent consisting essentially of a low-boiling paraffin hydrocarbon material at a temperature lying between about 30 and about 65° F. to selectively dissolve said hydrocarbon oil from said primary solvent, contacting resulting oil-denuded primary solvent with a second portion of said secondary solvent at a temperature lying between about 100 and about 150° F. to dissolve said mercaptans in said second portion of secondary solvent, and recovering said mercaptans from said secondary solvent.

4. A process according to claim 3 wherein said crude mercaptan oil comprises alkyl mercaptans

of at least four carbon atoms per molecule and olefins.

5. A method for recovering mercaptan from solution in an aqueous alcoholic alkali metal hydroxide solvent also containing dissolved therein a neutral organic liquid, which comprises contacting said solvent with liquid hydrocarbon at a temperature not greater than 65° F. to selectively transfer said neutral organic liquid from said solvent to solution in said hydrocarbon, separating the thus-treated solvent from said hydrocarbon and contacting same with liquid hydrocarbon at a temperature of at least 100° F. to transfer said mercaptan from said solvent to solution in said hydrocarbon, and recovering said mercaptan from said hydrocarbon.

6. A method according to claim 5 wherein said mercaptan comprises an alkyl mercaptan of at least eight carbon atoms per molecule, said neutral organic liquid comprises an olefin, the alcoholic constituent of said solvent is methanol, and said hydrocarbon to which said neutral organic liquid is transferred and said hydrocarbon to which said mercaptan is transferred is in each case a low-boiling paraffin.

7. A method according to claim 6 wherein said alkali metal hydroxide is sodium hydroxide.

8. A method according to claim 6 wherein said alkali metal hydroxide is potassium hydroxide.

9. A process for separating mercaptans from admixture with substantially neutral organic

liquids which comprises contacting such an admixture with an aqueous alcoholic alkali metal hydroxide primary solvent to dissolve at least part of said mercaptans together with at least part of said neutral organic liquid in said primary solvent, contacting the resulting mercaptan-rich primary solvent at a low temperature not greater than about 65° F. with sufficient of a first liquid hydrocarbon secondary solvent to selectively dissolve substantially all of said neutral organic liquid from said primary solvent, then contacting the so-treated primary solvent with a second liquid hydrocarbon secondary solvent at an elevated temperature of at least about 100° F. to transfer said mercaptans from said primary solvent to said secondary solvent, and recovering said mercaptans from said second liquid organic secondary solvent.
